UNITED STATES PATENT OFFICE.

WALTER J. KRENTNER, OF CHICAGO, ILLINOIS.

PRINTING-PRESS-CONTROLLING DEVICE.

1,231,747.

Specification of Letters Patent.

Patented July 3, 1917.

Application filed March 22, 1916. Serial No. 85,777.

To all whom it may concern:

Be it known that I, WALTER J. KRENTNER, a citizen of the United States, and a resident of the city of Chicago, in the county of Cook and State of Illinois, have invented certain new and useful Improvements in a Printing-Press-Controlling Device; and I do hereby declare that the following is a full, clear, and exact description of the same, reference being had to the accompanying drawings, and to the numerals of reference marked thereon, which form a part of this specification.

The purpose of this invention is to provide a mechanism adapted to form a part of or to be attached upon a printing press to improve the press work and obtain a uniform color impression on every sheet of stock by insuring proper inking of the form, preventing admission of an excess of ink thereto except where conditions so necessitate, and insuring a positive and sufficient supply of ink thereto to prevent pale impressions. There are many unfavorable conditions of operation which contribute to unsatisfactory printing, such as poor stock with the edges torn or worn, sheets sticking together, scraps in the stock, static electricity in the stock, the hand or automatic feeder weak or unreliable, and poor delivery of the stock after an impression is made thereon. Any of the above conditions necessitates tripping the machine to elevate the impression roller away from the form, thus causing the form to be successively inked without impressions being taken therefrom, causing the form to fill up with ink, and subsequently, due to the excess ink, causing offset and otherwise poor impressions to be made on the stock which is otherwise good in all respects. My invention obviates trouble arising from any of the above conditions enumerated, and further insures a saving of large quantities of ink and stock.

Briefly stated, the control device acts to check the doctor roll of the press in its movement for contact with the fountain roll, and furthermore to raise the form ink rolls when the press is tripped, out of possible contact with the form or ink plate, and operating to permit more than one rolling or inking of the form for each impression taken from the form, if so desired.

It is an object therefore of this invention to construct a controlling device for printing presses adapted to prevent an excess inking

of the form when the press is tripped, and further provided with a means to permit an excess supply of ink to the form over that usually supplied for one rolling thereof in instances, as for example, when the form or ink plate has been washed.

It is also an object of this invention to provide a control device for a printing press adapted for connection to the tripping mechanism of the press whereby successive ink rolling operations on the form are prevented when the press is tripped, that is, so that no impressions are taken therefrom and with means capable of throwing the control device out of operation whereby the press is enabled to operate in the usual manner, that is, as constructed without adaptation of my invention thereto.

It is also an object of this invention to construct a control device for attachment on a printing press operating to control the supply of ink to the form, whereby a uniform inking of the form for each impression taken therefrom is assured and impressions of a constant and uniform color are obtained.

It is furthermore an important object of this invention to provide a controlling device for a printing press which is constructed for adjustment into three positions, one wherein the device remains idle, permitting the printing press to operate in the usual and ordinary manner, another position whereby an additional supply of ink may be rolled upon the ink plate but not the form when conditions so necessitate, and a third position wherein the device is connected for automatic operation with the press, so that in the event of tripping the press the control will operate to cause movement of the different inking mechanisms into neutral or idle position, so that an excess quantity of ink is not rolled upon the form or ink plate when no impressions are to be taken therefrom.

It is finally an object of this invention to construct an improved type of controlling device for adaptation to a printing press permitting a control of the ink supply to the form to be directly in the hands of the press operator, so that clean cut impressions of uniform color are at all times assured from the form.

The invention (in a preferred form) is illustrated in the drawings and hereinafter more fully described.

In the drawings:

Figure 1 is a fragmentary side elevation of a press equipped with a mechanism embodying the principles of my invention.

5 Fig. 2 is a similar fragmentary view of the other side and of the other end of the press.

Fig. 3 is a fragmentary horizontal section illustrating, with parts in elevation and 10 parts in section, the mechanisms mounted in the lower framework of the press.

Fig. 4 is a fragmentary detail section taken on line 4—4 of Fig. 3.

Fig. 5 is a detail section taken on line 15 5—5 of Fig. 3.

Fig. 6 is a detail section taken on line 6—6 of Fig. 3.

Fig. 7 is a fragmentary detail section taken on line 7—7 of Fig. 2.

20 Fig. 8 is a fragmentary side view of the rack which is attached to and moved with the form table.

Fig. 18 is a fragmentary top plan view of a portion of the mechanism shown in Fig. 16.

45 Fig. 19 is a fragmentary enlarged detail view of the handle controlling lever shown in Fig. 1.

Fig. 20 is a sectional detail on line 20—20 of Fig. 3.

50 Fig. 21 is a detail of the form ink rolls support.

As shown in the drawings:

The main frame of the machine consists of a base 1, having a plurality of integral uprights 2, which at their upper ends are 55 integral with a table or bed frame 3, on which the form and inking plate are slidably mounted in a usual manner. Substantially at the middle of the bed frame 3, of the press, upright frame members 4, are provided on each side thereof within which are 60 slidably mounted bearings 5, in which a large feed or impression roller 6, is journaled. The bearings 5, and the feed roll 6, are normally held elevated by coiled compression springs 7, disposed around guide 65

uprights 8, which extend down to the base 1, of the frame. Journaled transversely of the base 1, beneath the roller 6, is a shaft 9, having eccentrics thereon over which are journaled bearing members 10, which are 70 connected by means of the uprights 8, to the bearing members 5, so that when the eccentric shaft 9, is rotated, the roll 6, is moved downwardly against the compression of the springs 7, to move a sheet of stock disposed 75 on said roll against the inked form in the bed frame 3, of the machine.

The tripping mechanism of the press whereby rotation of the eccentric shaft 9, is prevented so as not to impel the impression roller 6, downwardly, consists of an upright lever 11, shown in Fig. 1, having a foot pedal 12, on the upper end thereof, and the lower end of said lever 11, is pivoted to a long crank 13. Said crank 13, is secured 80 upon a shaft 14, which extends transversely through the base 1, of the machine, and on the opposite side thereof is provided with a curved guide link 15. Also journaled transversely of the base 1, is a shaft 16, provided with a large driving gear 17, and on the rear surface of which, as shown in dotted lines in Fig. 2, is a continuous cam recess 18. A short lever 19, is journaled on the eccentric shaft 9, and provided with a 85 roller adapted to move in the recess 18, and pivotally connected to the outer end of said lever 19, is a curved lever 20, provided with a roller at its end adapted to move in the recessed guide link 15. Said curved lever 20, 90 is also provided with a notch on its under side, and rigidly secured upon the eccentric shaft 9, is a collar having a projecting tooth or lug 21, normally engaged with the notch in said curved lever 20, so that movements of 95 the lever 19, causing movements of the lever 20, will in turn cause movement of the tooth 21, to oscillate the eccentric shaft 9. Tripping of the machine, which merely prevents lowering of the press roll 6, is effected by 100 depressing the foot pedal 12, which, through the lever 11, and crank 13, rotates the shaft 14, to move the curved guide lever 15, outwardly to the left from the position shown 105 in Fig. 2, whereupon when the swinging 110 movements of the levers 19 and 20, take place the roller at the end of the lever 20, will roll outwardly in the shifted guide lever 15, so that the lever 20, will be moved out 115 of engagement with the tooth 21, and therefore will not impart an oscillating movement to the eccentric shaft 9. This form of driving mechanism whereby the feed roll 6, is moved downwardly for an impression, is merely a conventional type, as well as the 120 means for the so-called tripping operation provided for the purpose, and it is obvious that any well known mechanism for performing the purpose such as used in any 125 press whatsoever may be utilized, 130

The idea of my invention is to control the inking operations performed upon the form, that is, preventing the same being over-inked or filled up with ink when no impressions are taken therefrom, and providing a means also for permitting more than a single inking or rolling operation to take place thereon when desired, as for instance in placing the machine in operation 10 after the form or ink plate has been washed. The inking mechanisms are only illustrated in a conventional manner, and of course may be different for different types of presses.

15 For this purpose, at one end of the frame of the machine an ink basin or reservoir 22, is provided, within which a fountain roll is mounted on a shaft 23, and adapted to rotate therewith, the lower surface of the roll 20 being submerged in the ink in the reservoir. A shaft 24, is journaled transversely of the frame of the machine, and has secured on one end thereof, as shown in detail in Fig. 12, a double crank comprising arms 25 and 25 26, the arm 25, affording a support for one end of a pivotally mounted ductor roller 27, which, when in lower position, contacts with the fountain roller on the shaft 23, of the ink reservoir, to receive a supply of ink 30 therefrom. The other arm 26, of said crank has adjustably and pivotally connected therein a curved arm 28, which is secured to a long connecting rod 29, and with the other end of said connecting rod 29, provided with a yoke or fork 30, on one side of which is a roller 31, tracking in a cam groove 32, of the cam wheel 33, secured upon the shaft 16. Journaled upon the eccentric shaft 9, is a sector shaped cam or stop member 34, a portion of the periphery of which, as clearly shown in Fig. 12, is of a less radius than the other, and said sector member is adapted to swing downwardly to contact with one of the forked ends of the 45 yoke 30, to hold the same from sliding movement into its extreme inner position. When so holding the yoke, the sector shaped element is in the dotted line position shown in Fig. 12, and the ductor roller 27, is thereby 50 held from movement into contact with the roller on the shaft 23. The hub of the sector member 34, is provided with a clutch jaw or dog 35, as shown in detail in Fig. 5, and a collar is rigidly secured upon the eccentric shaft 9, and provided with a clutch jaw or dog 36, so that the oscillating movement of the eccentric shaft 9, may, when the respective jaws 35 and 36, are in contact 55 with one another, oscillate the sector member 34. However, means are provided for moving the sector member 34, upwardly into a position such that the dogs 35 and 36, are out of contact and the oscillations of the shaft 9, are not transmitted to the sector member, and the sector member will thereby 60 65

not interfere with the sliding movement of the forked yoke 30.

For this purpose, a pin 37, is provided on one surface of the sector member 34, and engages in the slotted end of a lever or link 70 38, which is pivoted to the end of a short crank 39, secured upon a shaft 40, journaled horizontally and transversely at the base of the machine. The other end of said shaft 40, is shown in Fig. 1, and secured thereon 75 is a short crank 41, which is connected by means of a long upright member 42, to a crank arm 43, of a handle or actuating lever 44, pivoted on a stud shaft 45 at the upper end of the frame member 4. A curved 80 guard plate or bar 45^a, is mounted adjacent the handle lever 44, and has the three possible positions of the handle lever 44, designated by the numerals 1—2—3. Connected to be actuated simultaneously with and by 85 the shaft 40, due to adjustments of the handle 44, is an inclined or angled cam sector 46, journaled on the shaft 9, as shown in Figs. 3, 4, and 6, and provided with a dog 47, on the hub thereof adapted to be contacted by a dog 48, of a collar secured rigidly upon said shaft, so that when said sector cam is in certain position with the dogs in contact with one another, the sector will 90 be oscillated by the shaft similarly to the 95 movement imparted to the sector 34, previously described.

For the purpose of shifting said sector cam 46, due to actuation of the shaft 40, a relatively long stud or pin 49, is provided 100 on the rear surface of said sector cam, extending outwardly therefrom parallel to the shaft 9, and pivotally engaged thereon is the slotted end of a lever or link 50, the other end of which is pivoted on a short 105 crank 51, secured upon said shaft 40. The purpose of said sector cam 46, is to transfer a longitudinal movement to a rectangular bar or key 52, which is slidably mounted through a portion of the frame slightly 110 above and parallel to the crank shaft 9, and notched on its under surface for engagement with the periphery of the sector 46.

As shown in Figs. 3 and 7, a long slidable 115 rack bar 53, is disposed centrally and longitudinally above the base 1, of the frame, and is connected by means of uprights, one 54, of which is shown, rigidly to the slidable table on which the form and inking plates of the press are mounted. Extending transversely through the rack bar is a shaft 55, and mounted on one end thereof on one side of the rack bar is a pawl 56, and on the other end of said shaft on the other side of the rack bar is a disk 57, having a coiled 120 tension spring 58, connected to an extension thereof and to a stationary pin in the rack bar, the purpose of said spring being to hold said pawl 56, in either one of its extreme 125 positions beyond dead center thereof. 130

Journalized on the end of the shaft 55, on which the pawl 56, is mounted, is a collar 59, having a projection 60, thereon, and a portion of said collar 59, is cut away to permit a certain lost motion thereof with respect to the pawl 56. A leaf spring 61, is mounted on the surface of said pawl and bears upon a pin on said collar, acting to hold the same normally in one extreme position of its movement with respect to said pawl. A projection 62, is also provided upon the disk 57, projecting outwardly therefrom for a purpose hereinafter pointed out.

15 Mounted at one side of the rack bar 53, rigidly upon the base of the press frame, and rearwardly of the position of the key 52, is a Z-bracket 63, having pivotally mounted on its upper end a latch pawl 64, which normally projects into a position to engage the stop or projection 62, when the same is disposed in position for contact thereby, to swing the pawl from the position shown in Fig. 3, to that shown in Fig. 8, and a coiled tension spring 65, is connected to the tail of said latch pawl 64, to hold the same normally in position for engagement and yet permitting the stop 62, to track forwardly thereover by swinging said latch pawl against the stress of its spring. The pawl 56, when swung upwardly into the position shown in Fig. 17, is adapted to strike against a roller 66, mounted on a crank 67, which is secured rigidly on a shaft in a bearing member 68, on the base 1. Mounted upon the other end of the shaft on which the crank 67, is secured, is a crank 69, which has pivoted thereto a long link or lever 70, which is in turn pivoted to another crank 71, secured rigidly upon a transverse shaft 72, journaled across the base of the machine. Said shaft 72, at each of its ends is provided with a short crank 73, to each of which are pivotally connected upwardly extending levers 74.

The form inking rollers of the press are all denoted by the reference numerals 75, and are mounted transversely of the press in bearing brackets 76, provided on each side 50 of the press, said bearing brackets being vertically movable so as to elevate the inking rolls away from the form and ink plate when so desired. As shown in Figs. 13 and 14, each bearing bracket 76, normally rests 55 upon the top surface of a frame member 3, and when elevated therefrom is guided by guide bolts 77, threaded into the frame member 3, through recesses provided therefor in the bearing brackets 76. The elevation of 60 each of the bearing brackets 76, is effected by rotation of eccentric shafts 78, which are seated in registering recesses between the bearing brackets 76, and the frame member 3, as shown in Fig 14, so that when said respective shafts 78, are rotated, the bearing

brackets 76, are elevated away from the frame. Said shafts 78 are simultaneously actuatable, and the shafts of each pair are connected by a connecting rod or lever 79, pivoted to cranks 80, secured upon the ends 70 of each of the shafts 78. Also connected to each end of one of the shafts 78, of each pair thereof is a crank 81, to which the upper ends of the upright levers 74, are pivotally connected, whereby the rotational movement is imparted to the respective shafts 78, from the shaft 72, for the purpose of elevating the inking rolls 75. As shown in Figs. 3 and 7, said shaft 72, is provided with counterweights 72^a, to offset the weight 80 of the bearing brackets 76, and ink roll 75, when elevated by the eccentric shafts 78. The inking rollers for the ink plate which moves with the form to transfer ink to the form inking rolls 75, are mounted at one 85 end of the machine and denoted by the reference numerals 82, and one thereof is positioned to receive the ductor roll 27, moved into contact therewith after the same has contacted with the roll within the reservoir 90 22, to transfer the ink thereto, whereby the ink is in turn transferred to the other of the rolls 82, and distributed over the ink plate when it slides therebeneath.

Pivotedly mounted at one side of the machine are a pair of levers 83, each adapted to release one of two crank levers, having arms 84 and 85, which are pivoted on one of the bearing brackets 76. Said crank levers are of slightly different shape, but are 100 identical in operation, the purpose thereof being to elevate the two uppermost rolls 86, of the ink rolls 75, out of contact with the others of the group, and said crank levers perform this function when the levers 105 83, are swung rearwardly to permit the arms 84, to swing downwardly by gravity. Each of the levers 83, is provided with a spring impelled safety latch arm 87, which hooks over the roller on the end of the crank arm 110 84, to prevent retraction thereof out of engagement with the lever 83, when the bearing brackets and ink rolls are elevated by the eccentric shafts 78.

The operation is as follows:

When the machine is operating, that is, when impressions are being taken from the inked form, the feed or press roller 6, is depressed to move the stock which is held thereon into engagement with the form to 120 receive an impression therefrom, said roller being moved downwardly at periodic intervals for the purpose, rotating as the form slides therebeneath. In the event that the machine is tripped, that is, by the operator 125 depressing the pedal 12, the guide lever 15, is swung outwardly and as a consequence the oscillating drive to the eccentric shaft 9, received from the cam gear 17, is disconnected and the eccentric shaft 9, remains at 130

rest with the press roller 6, in an elevated position. The hand lever 44, at this time is in its first position or that shown in Fig. 19, and when so disposed the position of the shaft 40, actuated thereby through the link 42, is such that the sector cam 34, is permitted to oscillate with the eccentric shaft 9, when the same oscillates, due to the fact that the dog 35, on said section cam rests 5 against the dog 36, on the collar rigid on the shaft 9, and the shaft 40, being in the position aforesaid, the link 38, is so disposed that the pin 37, of said sector 34, merely slides in the slotted end of the link 38. The 10 shaft 9, however, when coming to rest, leaves the sector 34, in its lower or dotted line position shown in Fig. 12. As a consequence, the inwardly moving fork or yoke 30, which is actuated due to its roller traveling in the 15 suitable linkage connections to said forked yoke 30, is held elevated away from the fountain roller on the shaft 23, that is, in the dotted line position shown in Fig. 12, and as a consequence no ink is transferred to the ink rolls 82. When the shaft 9, is at 20 rest, due to the machine being tripped, the inclined sector cam element 46, thereon, shown clearly in Fig. 3, is in a position such that the key 52, is held thrust inwardly toward the rack bar 53. During the usual 25 oscillating movements, however, of the shaft 30 9, the sector 46, oscillates therewith in the manner described with reference to the sector 34, due to the fact that the dog 47, on the sector 46, rests against the dog 48, on a collar rigid on the shaft 9, and the pin 49, 35 on said sector 46, slides backward and forward in the slotted end of the lever 50, without hindrance, thus periodically retracting the key 52.

However, as stated, when the shaft 9, is 40 brought to rest due to a tripping operation, the key 52, is left in an inwardly thrust position, and as a consequence the rearward movement of the rack 53, causes said key 52, to strike the stop 60, on the pawl 56, which 45 is on one side of said rack bar, throwing the pawl upwardly to its upward position, such as shown in Fig. 17, the spring 58, on the opposite side of the rack bar 53, as shown in Fig. 9, serving to hold said pawl in its upward position beyond dead center. The 50 pawl so disposed upon the rearwardly moving rack bar, is in a position to strike the roller shown in Fig. 17, on the end of the crank 67, as clearly shown in Fig. 3, thus 55 rotating the same and with it the crank 69, thereby actuating the long link or lever 70, and through the crank 71, rotating the shaft 72. The slight rotational movement imparted to the shaft 72, is transmitted 60 through the cranks 73, and upright levers 65 74, to the eccentric shafts 78, thereby elevating the roller bearing brackets 76, thus elevating the form inking rolls 75, away from possible contact with the form and ink plate. The return reciprocating or forward movement of the rack bar 53, causes the stop 62, on the opposite side of the rack bar from the pawl 56, to strike against the latch 64, thereby throwing the pawl 56, downwardly, in which position it is held by the spring 58. 70 Each subsequent rearward reciprocating movement of the rack bar 53, causes the pawl 56, to be again thrown upwardly, so that in the sequence of operations, the inking rollers 75, are elevated away from possible contact with the ink plate and form at 75 the proper intervals, when the machine is in tripped condition. The result of the foregoing operation of the parts is that no ink is transferred to the rolls from the ink reservoir and no ink from the rolls to the inking plate and form when the machine has been tripped. 80

Assuming now, it is desired to permit the ductor roller 27, to transfer ink to the ink 90 rollers 82, to ink the ink plate, as for instance after the same has been washed, and yet not permit the rollers 75, to move downwardly into a position to ink the form. The handle lever 44, is then moved into its second 95 position, thus causing an adjustment of the shaft 40, whereby the crank 39, thereon shifts the lever 38, rearwardly to elevate the sector 34, sufficiently such that the same cannot move downwardly by gravity an 100 amount sufficient to check the entering movement of the fork member 30, thus permitting the ductor roller 27, to move into contact with the fountain roller on the shaft 23, and to effect a transfer of ink to the rolls 105 82. However, such adjustment of the shaft 40, does not cause sufficient movement of the link 50, through the crank 51, on said shaft 40, to move the sector cam 46, so that as a consequence the same remains in a position 110 to hold the key 52, inwardly, and thereby operates the mechanism when the rack bar 53, oscillates to periodically elevate the inking rollers 75, out of possible contact with the form or ink plate of the machine. 115

Next assume that it is desired to also ink the form as well as the ink plate, as for instance after the form has been washed, and no impressions are to be taken immediately therefrom, or, for example, to deepen the 120 color of the impression to be taken from the form, then the hand lever 44, is moved into its third or extreme position. With the hand lever in this position the shaft 40, will be so adjusted that the link 38, will be moved 125 rearwardly to hold the sector member 34, out of possible contact with the fork 30, so that reciprocation of the ductor roll 27, will take place as the press operates, even though the press has been tripped. This 130

adjustment of the shaft 40, will cause the slotted link 50, to be likewise moved rearwardly an amount to draw the sector member 46, upwardly to hold the key 52, retracted, and as a consequence the pawl 56, on the rack bar will not be thrown upwardly to actuate the crank 67, to cause, through the link 70, cranks 71 and 73, and lever 74, the eccentric shafts 78, to be actuated, thereby allowing the ink rolls 75, to remain in normal inking position. It is apparent therefore that with the hand lever 44, in its third position and with the press tripped, ink will be transferred by the ductor roll 27 to the rolls 82, and by the rolls 82, and ink plate to the ink rolls 75, which will in turn apply the ink upon the form.

The entire operation of the machine may be summed up as follows: that is, under ordinary conditions when the machine is tripped to hold the feed roll 6, elevated, mechanisms operate to prevent transfer of ink by the ductor roll 27, to the rolls 82, and furthermore the rolls 75, are elevated away from possible contact with the form and ink plates, but either the ink plate or form, or both the ink plate and form, may be inked by effecting first a transfer of ink only to the rolls 82, for the ink plate and secondly by permitting the rolls 75, to contact with the plate and form to receive ink from the plate and transfer the same to the form.

I am aware that various details of construction may be varied through a wide range without departing from the principles of this invention, and I therefore do not purpose limiting the patent granted otherwise than necessitated by the prior art.

40 I claim as my invention:

1. In a printing press, a reservoir, a fountain roller, a ductor roller, ink transfer rollers, reciprocating inking and form

plates, and form inking rollers, of controlling mechanism adapted, when in one position, and the press is tripped, to cut off the ink supply by breaking contact between said fountain and ductor rollers, and when in another position to permit the ink supply and the contact between the transfer rollers and the inking plate, but to break contact between the form inking rollers and the form plate.

2. In a printing press, a reservoir, a fountain roller, a ductor roller, ink transfer rollers, reciprocating inking and form plates, and form inking rollers, of controlling mechanism adapted, when in one position, and the press is tripped, to cut off the ink supply by breaking contact between said fountain and ductor rollers; when in another position to permit the ink supply and the contact between the transfer rollers and the inking plate, but to break contact between the form inking rollers and the form plate; and when in a third position to reestablish contact between said form inking rollers and the form plate also.

3. In a printing press, an oscillatable rack bar, a pawl mounted on the rack bar, means operating to cause a shifting of said pawl when the press is tripped, mechanism operated by the shifted pawl to move the ink rolls of the press out of inking position, and mechanism acting periodically to shift said pawl shifting means out of shifting position during the reciprocating movements of the rack bar when the press is operating under normal conditions.

In testimony whereof I have hereunto subscribed my name in the presence of two subscribing witnesses.

WALTER J. KRENTNER.

Witnesses:

CHARLES W. HILLS, Jr.,
EARL M. HARDINE.
